UNITED STATES PATENT OFFICE.

JACOB SICKLER, OF OTTERBEIN, INDIANA.

SAND-AUGER.

SPECIFICATION forming part of Letters Patent No. 297,642, dated April 29, 1884.

Application filed February 12, 1884. (No model.)

To all whom it may concern:

Be it known that I, JACOB SICKLER, a citizen of the United States, residing at Otterbein, in the county of Benton and State of Indiana, 5 have invented a new and useful Improvement in Sand-Augers, of which the following is a specification.

My invention relates to a means for removing sand, slush, and gravel from bored wells; 10 and its object is to overcome the difficulty of a stone or gravel getting in the valve of the common pump and letting all the load out as it is raised from the well.

The accompanying drawings illustrate my 15 invention.

Figure 1 is an elevation of my improved auger. Fig. 2 is a section of the auger and well, showing the operation of the auger.

20 *a* is a thin metallic cylinder having its lower end flat and closed, as shown, while the upper end is left open. A socket, *b*, is cast on the inside of the cylinder in the center of the bottom. In this socket is firmly secured a wrought-iron shaft, *c*, passing up through the cylinder, 25 and having an eye in its upper end, whereby it may be hinged to the boring-shaft *d* of a common well-boring auger. A band, *e*, is adapted to slip down over this joint, holding it rigid while in operation. Two thin spiral 30 flanges, *f f*, are cast integrally with the cylinder *a*. These flanges begin in the center outside of the bottom, and extend outward to the circumference of the cylinder, thence upward spirally to the top of the cylinder, thus forming two auger-lips at the bottom and two inclined planes on the outside of the cylinder. The cylinder *a* is made about one-sixth smaller 35 than the bore of the well-tube, and the flanges *f f* are made wide enough to fill the space between the cylinder and the well-tube *g*. The 40

upper ends of these spiral flanges stop level with the top of the cylinder. The lower ends are flattened and sharpened similar to ordinary auger-lips. Space enough is left between the spiral flanges and the well-tube to allow 45 the auger to pass freely up or down inside the tube.

The operation is as follows: The auger is attached to the ordinary well-boring auger-shaft, *d*, and lowered to the bottom of the well. When it is turned, its weight and the weight 50 of the shaft force it down into the sand. The spiral flanges take up the sand and pebbles as the cylinder is turned, raising them to the top, when they pour into the cylinder. The auger is now raised from the well, the band *e* is slipped upward off of the joint, and the auger 55 may be inverted for emptying.

I claim as my invention and desire to secure by Letters Patent—

60 1. The combination of the hollow cylinder *a*, closed at the bottom, flanges *f f*, socket *b*, shaft *c*, shaft *d*, and band *e*, adapted to holding *c* and *d* rigid, all substantially as shown and described.

65 2. A sand-auger consisting of a hollow cylinder, *a*, closed at the bottom, having two sharpened lips on the bottom, and having two spiral flanges wound upon it externally from the top to the center of the bottom, and forming a hollow auger adapted to being moved freely inside of a well-tube, and to being attached to a common well-boring auger-shaft, 70 substantially as shown and described, and for the purpose set forth.

JACOB SICKLER.
